[57] CLAIM

[21] Appl. No.: 29/077,404

The ornamental design for golf bag insert with fifteen club partitions, as shown and described.

[22] Filed: Oct. 2, 1997

DESCRIPTION

[51] LOC (6) CL 03-99

FIG. 1 is a perspective drawing illustrating a golf bag insert with fifteen club partitions, showing my new design; the opposite side view being a mirror image thereof; and, FIG. 2 is a top end view of thereof, the bottom end view being plain and unornamented.
